BY

Richard J. Oliver,

ATTORNEY

UNITED STATES PATENT OFFICE.

RICHARD J. JOHNSON, OF LAKE BENTON, MINNESOTA.

SMOKE-WASHER.

1,289,797.

Specification of Letters Patent. Patented Dec. 31, 1918.

Application filed March 1, 1918. Serial No. 219,929.

To all whom it may concern:

Be it known that I, RICHARD J. JOHNSON, a citizen of the United States, residing at Lake Benton, in the county of Lincoln and 5 State of Minnesota, have invented certain new and useful Improvements in Smoke-Washers, of which the following is a specification.

This invention relates to smoke washers 10 which may be used in connection with any source of smoke supply, such as a smoke stack.

The object of the invention is to provide a simple and efficient apparatus of this character which will thoroughly mix and dissolve the products of combustion in water and then discharge the water into a sewer or other suitable place of deposit where it will be harmless.

20 Another object is to provide an improved mixer or washer of this character whereby the smoke and other combustion products discharged thereinto will be effectively agitated and commingled with water contained 25 therein.

With the foregoing and other objects in view, which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the invention. 35

In the accompanying drawings:

Figure 1 represents a vertical section of a washer constructed in accordance with this invention.

40 Fig. 2 is a horizontal section taken on the line 2-2 of Fig. 1, and

Fig. 3 is a similar view taken on the line 3-3 of Fig. 1.

In the embodiment illustrated, the apparatus constituting this invention may be connected with any source of smoke supply (not shown), such as a boiler or other furnace smoke stack.

50 The apparatus constituting this invention comprises a closed casing 1 having a discharge outlet 1^a at its upper end which is designed to be connected with a pipe (not shown), which conveys the water and the unaffected gases discharged through the casing 55 to a sewer or other suitable place of deposit.

A pipe 2 enters the washer or mixing casing 1 through the top thereof and extends to a point near its bottom where it is provided with lateral oppositely disposed extensions 60 3 and 4 having upturned mouths 5 through which the products of combustion entering through pipe 2 are designed to be discharged.

Revolutely mounted on the end of the pipe 65 2 which is disposed within the mixer is an agitator in the form of a plurality of reticulated vanes 6 which radiate through collars 7 and 8 revolutely mounted on said pipe end 2. Any desired number of these 70 vanes 6 may be employed, four being preferably used, and the mouths 5 of the pipe extensions 3 and 4 are disposed adjacent the lower ends of said vanes and are designed to discharge their contents in the path of the 75 vanes so that the revolutions thereof will operate to thoroughly commingle the products so discharged with the water contained in the mixer.

A bevel gear 9 is fixed to the collar 7 and 80 meshes with a bevel pinion 11 carried by a shaft 10 which extends laterally through one side wall of casing 1 as shown clearly in Fig. 3 and by means of which motion is imparted to the mixing vanes. Motion is im- 85 parted to this shaft 10 by any suitable means (not shown).

A water supply pipe 12 enters the casing 1 at the lower end thereof and is connected at its other end with any suitable source of 90 supply (not shown), so that water may be continuously supplied to the casing 1, entering at the bottom thereof and overflowing at the top through pipe 1^a.

In the operation of this apparatus, motion 95 being imparted to shaft 10 by a source of power (not shown), will cause the vanes 6 to rotate within casing 1 and the products of combustion entering through pipe 2 will be thoroughly commingled by the revolutions of said vanes with the water in the casing 1. When these products of combustion have been thoroughly commingled and dissolved in the water of the mixer they pass out with the water through pipe 1^a to a suitable place of deposit. 100

From the foregoing description, taken in connection with the accompanying drawings, the advantages of the construction and of the method of operation will be readily 110 apparent to those skilled in the art to which the invention appertains and while I have

described the principle of operation of the invention together with the device which I now consider to be the best embodiment thereof, I desire to have it understood that 5 the device shown is merely illustrative and that such changes may be made as are within the scope of the claimed invention.

I claim:

1. In a smoke washer, the combination of 10 a closed water containing chamber having an outlet at its upper end, a pipe extending into said casing for supplying products of combustion thereto, said pipe having a lateral extension provided with an upturned mouth, and agitator means revolubly mounted on said pipe above said mouths and against which the contents of said pipe are discharged.
2. In a smoke washer, a closed water containing mixing chamber having an inlet at 20 its lower end and an outlet at its upper end, a pipe extending into said chamber through

the top to a point near its bottom, said pipe having lateral extensions provided with upturned mouths, and a plurality of agitator 25 vanes revolubly mounted on said pipe above said mouths and against which the contents of said pipe are discharged.

3. An apparatus of the class described including a closed casing having an outlet pipe 30 at its upper end and adapted to contain a washing fluid, a smoke pipe extending into said casing through the top thereof and provided at its lower end with laterally extending branch pipes having upturned mouths at 35 their free ends, reticulated agitators mounted to rotate on said pipe above said mouths, and means for actuating said agitators.

In testimony whereof I affix my signature in presence of two witnesses.

RICHARD J. JOHNSON.
